METALLIC RECEPTACLE AND CLOSURE THEREFOR

Filed July 9, 1934

UNITED STATES PATENT OFFICE

2,162,663

METALLIC RECEPTACLE AND CLOSURE
THEREFORWilliam Lockhart, Cleveland, Ohio, assignor to
Cornell Securities Corporation, Cleveland,
Ohio, a corporation of Delaware

Application July 9, 1934, Serial No. 734,286

7 Claims. (Cl. 220—61)

My invention is an improvement in metallic receptacles and closures therefor, and relates more particularly to means for removably securing the closure in place upon the open end of the receptacle in fluid tight sealed relation thereto.

One of the objects of this invention is to provide means for quickly securing a cover on a metallic receptacle such as a barrel or drum of the full removable head type, wherein the means may be operated in a step by step movement to deliver varying pressures to the cover. This is particularly desirable where the barrel manufacturer is required to ship the drums with the covers applied under only a light pressure sufficient to hold the cover in place for shipping empty and where the user subsequently desires to apply the full closing or sealing pressure as in shipping the containers filled to its customers.

Another object is to construct a simple and positive means for carrying out the above object.

A further object is to provide a rack and pinion operated ring closing device wherein the pinion may be selectively operated in reverse directions and intermittently to apply or release cover sealing pressures to the cover and drum.

A still further object is to produce such means which operate within the circumference of the drum and which is sturdy and durable in use and which also is inexpensive to manufacture.

Other objects and advantages of my invention will become more apparent as the following description of an embodiment thereof progresses, reference being made to the accompanying drawing, in which like reference characters are employed to designate like parts throughout the same.

In the drawing:—

Figure 1 is a top plan view of a device embodying my invention and shows the same applied in use;

Figure 2 is an enlarged section taken on line 2—2 of Figure 1, and illustrates how the locking ring engages the cover flange and the bead of the drum to press the same firmly together when the ring is contracted;

Figure 3 is a fragmentary view partly in section showing the position of the ends of the split locking ring when the ring is contracted and also illustrates one form of means for contracting and/or expanding the ring in accordance with my invention;

Figure 4 is a view similar to that shown in Figure 3 but shows the ring expanded;

Figure 5 is a section taken on line 5—5 of Figure 3; and,

Figure 6 is a section taken on line 6—6 of Figure 4.

I have illustrated in the accompanying drawing one embodiment of my invention and have shown the same applied to a metallic shipping drum 1, the upper open edge of which is rolled or otherwise formed into a peripheral bead 2. A cover 3, comprising a cupped member having a peripheral upwardly and outwardly extending flange 4, is supported by the bead and the packing 5 in such a manner that the cupped portion of the cover may be telescoped for a short distance within the open end of the container or receptacle, as illustrated in Figure 2. It will be noted that a portion of the flange 4 is slightly arcuate in cross section to conform with the approximate curvature of the upper surface of the bead, and that the outer edge of the flange terminates at a point near that defined by the greatest outside diameter of the bead. The packing 5 may consist of an annulus of any suitable material such as rubber or cork. I find cork to be very satisfactory in use.

In the production and use of open end containers of the present type it is desirable that the cover be removably secured on the container in such a manner that a fluid tight seal between the cover, the packing and the bead may be made with ease, and with my invention such a seal between these parts is readily and effectively accomplished, as a further description of the present embodiment shown in the drawing progresses.

One simple means for removably securing the cover on the receptacle in fluid tight relation therewith, may include a split, channeled locking or clamping ring 6 which is substantially U-shaped in cross-section and is capable of being expanded and contracted by suitable operating means. The upper and lower flanges or walls of the cross-sectionally U-shaped ring which constitute the cover flange and bead engaging walls thereof, converge outwardly toward the arched portion of the ring as indicated more clearly in Figure 2.

This embodiment of my invention discloses a type of ring which is contracted to clamp the cover into fluid tight sealed relation with the drum or container, and is expanded to remove the ring and the cover from the drum, but it is to be understood that the invention disclosed herein may equally well be applied to a ring which is expanded to press the cover into sealed relation with the open end of the drum.

As illustrated, the contractible channeled locking ring is substantially U-shaped in cross sec-

tion and is split transversely, preferably at one point as indicated in Figure 1. Lugs or brackets 7 and 8 extend inwardly from the ring ends defining the split and may be formed integrally with the ring ends or may be formed separately and welded thereto.

Referring now more particularly to Figures 3 to 6 of the drawing I will proceed to describe more in detail the construction and operation of the embodiment illustrated therein and in particular the ring contracting and/or expanding means.

The lug or bracket 8 carried by one end of the split ring is preferably formed as indicated in Figure 6, that is, it is substantially U-shaped in cross-section providing an opening to permit the rack extension of the lug 7 to operate between the spaced walls 9 and 10 thereof. The walls 9 and 10 furthermore provide a suitable housing for the rack and the driving pinion and also serve as a guide for the rack in preventing vertical disalignment or distortion of the ring ends during the closing or opening movement, and provide means for maintaining the rack and pinion in proper meshing relation.

According to my invention I have provided a simple mechanism for expanding and/or contracting the split ring which consists essentially of a rack, a pinion and a selective means for driving the pinion in either direction of rotation. When it is desired to operate or drive the pinion in reverse directions, suitable means for disengagement of the operating means with the pinion is provided so that the pinion may be driven selectively in either of reverse directions.

The rack 11 is preferably formed integrally with the lug or bracket 7 and constitutes an extension thereof although it may be formed separately and secured thereto as by welding. The inner portion of the rack is toothed as at 12 and these teeth are preferably arranged in an arcuate series as illustrated, the ends 13 and 14 of the rack providing stops to limit the travel of the pinion or ratchet wheel 15 in opposite directions.

The pinion 15 is freely rotatably mounted between the spaced walls 9 and 10 of the lug or bracket 8 by means of a shaft or pin 16 passing through the walls 9 and 10 and the pinion 15. It will be noted from the drawing that the rack operates between the spaced walls 9 and 10 of the lug 8 and that its teeth are at all times in mesh with the teeth of the pinion.

A lever 17 is provided for rotating the pinion 15 in either direction and for this purpose is arranged to engage or disengage the pinion at the will of the operator. The lever constitutes an arm 17 shaped to conform substantially to the curvature of the ring when it is in the position shown in Figures 1 and 3.

The lever is formed at one end with a projection shaped to engage the pinion between any of the adjacent teeth thereof as shown at 18, Figure 4, to form a driving connection therewith. A fork like member 19 comprising a pair of plates 20 and 21, welded to opposite sides of the lever end, extends from this end of the lever on opposite sides of the projection 18 and is mounted to similarly embrace opposite sides of the pinion 15. As indicated more particularly in Figures 3, 4 and 6 the lever and member operate as a unit and constitute a sort of clutch in engaging and disengaging the projection 18 between adjacent teeth of the pinion 15. When these parts are in the position shown in Figure 3, that is, when the projection 18 is disengaged from the pinion, the

lever 17 is withdrawn but maintains a pivotal connection with the pin or shaft 16 which now engages the base of a T-shaped bearing slot 22 as at 23. In this position the lever is free to be operated in either direction without driving the pinion 15. But when the lever is thrust forwardly as in Figure 4 to engage the clutch projection 18 with the pinion, the pin 16 is removed from the base of the T slot and assumes a position such as is indicated in this figure. Thus when the lever is operated in either direction the pinion will be rotated and a corresponding relative movement between the rack and pinion takes place with the result that the ring is contracted or expanded according to the direction of movement of the lever and the position of the pawl 23a. For example, when the latch 24 is released, as in Figure 3, the pawl is in engagement with the teeth of the ratchet wheel or pinion to permit rotation of the pinion in one direction only. When the pinion is rotated in a clockwise direction, as in contracting the ring, the spring 25 permits the pawl to ride over the successive teeth of the pinion but prevents movement of the pinion in a counter-clockwise direction. In contracting the ring it may be necessary to throw the lever to the left several successive times depending upon the length of the rack in order to fully contract the ring. In such cases the pawl and pinion act as a ratchet device permitting free movement of the lever to the right.

Assuming that the ring has been fully contracted to press the cover in sealed relation to the container and that the ring will not readily spring open when the pawl 23a is released, as in Figure 4, the rack and pinion connection may be utilized to expand the ring by engaging the projection 18 with the teeth of the pinion and swinging the lever to the right. This is clearly shown in Figure 4. In this connection the pawl 23a may be held in retracted position by means of the link 24 pivoted at 26 to the pawl and having a slot 27 engageable with a pin 28 carried by the lug 8.

Of course, where the ring 6 is of the type which is expanded to press the cover and receptacle together in sealed relation, the pawl 23a may be reversed in position to permit intermittent normal operation of the pinion in a counter-clockwise direction. Otherwise the operation of the ring expanding means is substantially the same as above described in connection with the embodiment of the invention illustrated in the drawing.

It is to be noted that the projection 18 of the lever when in engagement between adjacent teeth of the pinion 15, affords sufficient clearance with the side walls of the teeth to permit the pin 16 to come to rest in one or the other recesses 29 and 30 forming the T-shaped slot 22, according to the direction of throw of the lever 17.

The herein described invention provides a simple direct power connection between the ends of a split clamping or locking ring and affords easy and quick operation of the device in either direction. By means of the ratchet-like action of the pinion and lever a fully contracted or expanded condition of the ring is readily attained while the lever may be brought to rest against the inner rim of the cover as in Figure 1. A suitable seal of inspection or the like may be applied as at 31.

Various changes in the details of construction and arrangement of parts may be made without

departing from the spirit of my invention or the scope of the appended claims.

I claim:

1. In a clamping device for a metallic receptacle having a bead around its open end and a cover having a flange fitting over the bead, a split channeled clamping ring to press the bead and cover flange together when the ring is contracted, and means for contracting the ring including a rack carried by one end of said ring, a pinion carried by the other end thereof and meshing with said rack, and a lever carried by said ring other end and slidable into and out of driving engagement with said pinion.
2. In a device for clamping a cover on a receptacle, a split clamping ring to press the cover on the receptacle when the ring is contracted, and means for contracting the ring including a stationary member carried by one end of the split ring, a rotatable member carried by the ring other end and having positive driving connection with said stationary member, and a lever having slidding engagement with said rotatable member for driving the same to contract or expand the ring.
3. A device for clamping a cover on the open end of a receptacle including a split locking ring engaging the cover and a portion of the receptacle to press the same together when the ring is contracted, and means for contracting said ring including a rack carried by one end of the ring, a pinion engaging the rack and rotatably carried by the other end of the ring, and a lever for rotating said pinion, said lever being slidable into and out of engagement with said pinion.
4. A device for clamping a cover on the open end of a receptacle including a split locking ring engaging the cover and a portion of the receptacle to press the same together when the ring is contracted, and means for contracting said ring including a rack carried by one end of the ring, a pinion engaging the rack and rotatably carried by the other end of the ring, a lever for rotating said pinion, said lever being slidable into and out of engagement with said pinion, and a latch to permit rotation of the pinion in one direction but preventing rotation in a reverse direction.
5. A device for clamping a cover on the open end of a receptacle including a split locking ring engaging the cover and a portion of the receptacle to press the same together when the ring is contracted, and means for contracting said ring including a rack carried by one end of the ring, a pinion engaging the rack and rotatably carried by the other end of the ring, a lever for rotating said pinion, said lever being slidable into and out of engagement with said pinion, and a pawl engageable with the teeth of the pinion to permit rotation of the pinion in one direction, but to prevent rotation thereof in an opposite direction.

6. A device for clamping a cover on the open end of a receptacle including a split locking ring engaging the cover and a portion of the receptacle to press the same together when the ring is contracted, and means for contracting said ring including a rack carried by one end of the ring, a pinion engaging the rack and rotatably carried by the other end of the ring, a lever for rotating said pinion, said lever being slidable with respect to the pinion and having a projection at or near an end thereof for driving engagement with said pinion, said lever also having an extended portion overlying the pinion, said portion having a T shaped slot therein to receive the shaft on which said pinion is rotatable, and a shaft for said pinion, said extended portion of the shaft having limited movement relative to and transversely of said pinion when said lever is operated to expand or contract the ring.

7. A device for clamping a cover on the open end of a receptacle including a split locking ring engaging the cover and a portion of the receptacle to press the same together when the ring is contracted, and means for contracting said ring including a rack carried by one end of the ring, a pinion engaging the rack and rotatably carried by the other end of the ring, a lever for rotating said pinion, said lever being slidable into and out of engagement with said pinion, and a pawl engageable with the teeth of the pinion to permit rotation of the pinion in one direction, but to prevent rotation thereof in an opposite direction.

WILLIAM LOCKHART.
